FIG. 1 is a front perspective view of a modular storage

unit showing my design.

FIG. 2 is an enlarged perspective view showing the

portion of the modular storage unit encircled by broken

line in FIG. 1.

The side and back of the modular storage unit not
shown in the drawing have the same plain appearance
as the top and side of the modular storage unit shown in
the drawing, with separation lines between the compo-

nents corresponding to those shown in the drawing.
